UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

SWITCH MECHANISM.

Original application filed June 9, 1920, Serial No. 387,626. Divided and this application filed December 17, 1921. Serial No. 523,067.

To all whom it may concern:

Be it known that I, JAMES M. BROWN, a citizen of the United States, and a resident of Pittsburgh, in the county of Allegheny and State of Pennsylvania, have invented a new and useful Improvement in Switch Mechanism, of which the following is a specification, this application being a division of my application Serial No. 387,626, filed June 9, 1920.

My invention relates to electrical protective and circuit-interrupting devices and particularly to circuit interrupters adapted for use with electrical farm equipment and other apparatus.

One object of my invention is to provide a circuit interrupter that shall comprise a plurality of relatively movable contact members and operating means for engaging and disengaging the same in predetermined sequence steps of permissibly different order during the opening and closing operations of the interrupter.

Heretofore, it has been usual, in connection with electrical farm service and other electrical equipments to provide an outdoor circuit interrupter or switch at or near the upper part of a pole or tower of a relatively high-tension transmission system. These interrupting devices usually include lightning arresters, limiting resistors, expulsion fuses and other means, for protecting the service circuit, which occasionally require attention such as the renewal of blown fuses, the replacement of damaged resistors and other repairs.

It is essential that the operators of these devices some of whom may be more or less unskilled and unacquainted with the characteristics of high-tension apparatus, be protected to the utmost.

To render the lighting and power equipment more effective and economical in service, it is desirable to provide transformers of different capacities and voltages for the main power-service lines and the lighting circuits, respectively, and to permit the operation of switches for connecting these transformers to their respective circuits from a position adjacent to the base of the transmission pole or tower. It is further desirable, in connection with electrical farm equipment, to have the operating means per-

manently connected to the interrupter and provided with locking means near its lower end, as this avoids the manipulation of the separate long pole in common use for operating disconnecting switches.

In practicing my invention, I provide a circuit interrupter having a plurality of sets of inter-related relatively movable contact members and operating means for selectively engaging and disengaging the contact members in different predetermined order. This permits the connection of either or both of different service transformers between the supply and service lines and also permits either of the transformers to be disconnected independently of the other. Means is also provided at an intermediate point on the pole or tower for preventing the approach of an operator to the interrupter when any of the contact members are engaged.

Figure 1 of the accompanying drawings is a diagrammatic view, in front elevation, of a device embodying my invention; and

Fig. 2 is a view thereof, in side elevation.

A circuit-interrupting device 1, supported on a cross arm 2 and a member 3, at the upper portion of a pole or tower 4, comprises ordinary pin-type insulators 5, stationary contact members 6 on the insulators 5, and a transverse shaft 7 having bearings in members 8 that are supported on the member 3. Sleeve members 9, 10 and 11, loosely mounted on the shaft 7, support the movable pole members 12, 13 and 14, respectively, of the interrupter 1. The sleeve member 10 has substantially half-cylindrical projecting portions 15 and 16 at its ends for co-operation with similar projecting portions 17 and 18 on the sleeve members 9 and 11, respectively, that are adapted to close the movable member 13 when either of the members 12 or 14 is actuated. Relatively long operating arms 19 and 20 are secured, by pins 21, to levers 22 and 23 of the sleeves 9 and 11, respectively, and extend to an operating device 24 disposed at a position adjacent to the lower end of the pole 4.

The operating device 24 comprises similar crank-handle members 25 mounted on opposite ends of a pin or shaft 26 extending through the pole 4 and having projections 27 for co-operation with brackets 28, and padlocks 29 or other means for locking the

interrupter in its closed position. Each of the movable members 12, 13 and 14 comprises a tubular insulating structure 30 in which an expulsion fuse 31 is connected in series with a supply line 32. Each contact member 6 is connected to a service line 33, and horn-gap members 34 and a limiting resistor 35 are operatively connected in series to ground through the metal members of the operating mechanism. The intermediate movable member 13 is provided with a weight member 36 or other means for opening the same when both of the members 12 and 14 are opened. The service lines 33 are connected to transformers 37 and 38 of different capacities, one of which may be used to energize a lighting circuit and the other to operate the heavier electrical-service devices.

20 A barrier 39, disposed at an intermediate position on the pole 6, has an open portion 40 permitting it to project in a horizontal plane on substantially all sides of the pole 4 and is pivotally mounted on a shaft 41 mounted in a bracket 42 that is secured to the pole 4 by bolts 43.

30 The barrier member 39 comprises a frame member or members 44 that extend transversely of the pole 4, a weighted portion 46 and depending lever members 47. Members 48 are secured to the barrier 39 and are bent downwardly and inwardly at their inner ends to connect with the lower ends of the levers 47. Transversely-projecting disks 49, or other means, are secured to the arms 19 and 20 to engage the members 48 on their upper sides.

40 When it is desired to connect the transformer 37 in circuit with the supply lines 32, one of the crank-handle members 25 is turned on the shaft 26 to move the arm 19 downwardly, during which movement the disk 49 on the arm 19 engages one of the members 48 to move the barrier member 39 to its horizontal position. At the same time,

the projection 17, on the sleeve 9, engages the projection 15 on the sleeve 10 to move the pole member 13 to its closed position simultaneously with the pole member 12. After this, the operating arm 20 may be moved to similarly move the pole member 14 to its closed position without affecting the position of the barrier member 39. It will be understood that this operation is reversible and that the members 13 and 14 may be initially closed simultaneously and the member 12 be moved to its closed position thereafter, but it will be seen that neither of the members 12 nor 14 may be moved alone to its closed position when all of the members 12, 13 and 14 are in their open position.

While I have shown and described a particular form of my invention, changes may be effected therein without departing from the spirit and scope thereof, as set forth in the appended claims.

I claim as my invention:

1. The combination with a pair of independently operable switch members having axially aligned interlocked pivot members and manually operable to open and closed positions, of a switch member yieldingly retained in open position and movable to closed position by either of the first said switch members.

2. The combination with a pair of switch members movable independently to open and closed positions and a switch member yieldingly retained in open position, of a rotatable sleeve for each switch for pivotally supporting the switch members and so interlocked that movement of either of the first said switch members to closed position moves the third switch member to closed position.

In testimony whereof, I have hereunto subscribed my name this 28th day of November, 1921.

JAMES M. BROWN.
